CORNHOLE LEVELING SYSTEM

BACKGROUND

The present invention relates to cornhole boards, and more specifically to a cornhole board leveling system.

Cornhole is a lawn game in which players or teams take turns throwing fabric bean bags or other items at a raised, angled board with a hole at an end. FIG. 1 shows a typical cornhole board 10. A single cornhole board 10 is preferably 2 by 4 feet (0.61 by 1.22 m), with a 6-inch (150 mm) diameter hole 3. The cornhole board 10 has a first end 2a opposite a second end 2b, and a top surface 2c opposite the bottom surface 2d, and two side surfaces 2h. The side surfaces 2h have a top edge 2i and a bottom edge 2j. Legs 4, 5 are attached to the second end 2b. A hole 3 is present along the top surface 2c and extends from the top surface 2c through to the bottom surface 2d. The hole's center is positioned 9 inches (230 mm) down from the center of the edge 2e of the board.

The legs 4, 5 have a first end 4a, 5a connected to the bottom 2d surface of the board 10 and the second end 4b, 5b which contacts the ground 6. It is noted that there is space between the legs 4, 5 and a back edge 2g of the second end 2b of the cornhole board 10. The second end 2b of the board 10 is a greater distance from the ground than the first end 2a. The legs 4, 5 are typically made of boards with a thickness of 1.5 inches (38.1 mm) or less and a maximum width of 3.5 inches (88.9 mm) since the boards are typical 2 ft (60.96 cm)×4 ft (121.92 cm). The front edge 2f of the first end 2a contacts the ground.

Each board 10 is angled with the back edge 2e of the playing surface 12 inches (300 mm) above the ground, and the front edge 2f three to four inches (76-102 mm) above the ground with an angle of 10 degrees. A standard court places the two boards 33 feet (10 m) or 27 feet (8.2 m) apart, measuring from the front edge 2f of the boards. The boards are often set up on a lawn which is not level, making placement and angling of the boards appropriately and fairly very difficult.

SUMMARY

According to one embodiment of the present invention, a kit for leveling one or more cornhole boards is disclosed. The kit comprises: at least one pair of back leg bracket assemblies and one or more front leg bracket assemblies.

The back leg bracket assemblies comprising: a right leg bracket assembly and a left leg bracket assembly. The right leg bracket assembly has a right leg having a right leg portion connected to a right leg base portion at a first angle; a right back leg bracket guide having a right leg guide body defining a closed end bore adapted to receive a right leg of a back of one or more cornhole boards and connected to a right leg guide defining a right leg through bore and a right leg screw bore perpendicular to and connected to the right leg through bore adapted to receive a screw; wherein the right leg portion of the right leg is received within the right leg through bore, such that the right leg guide is vertically adjustable about the right leg portion. The left leg bracket assembly has a left leg having a left leg portion connected to a left leg base portion at a second angle; a left back leg bracket guide having a left leg guide body defining a closed end bore adapted to receive a left leg of a back of one or more cornhole boards and connected to a left leg guide defining a left leg through bore and a left leg screw bore perpendicular to and connected to the left leg through bore adapted to receive a screw; wherein the left leg portion of the left leg is received within the left leg through bore, such that the left leg guide is vertically adjustable about the left leg portion.

bore adapted to receive a screw; wherein the left leg portion of the left leg is received within the left leg through bore, such that the left leg guide is vertically adjustable about the left leg portion; and

5 The one or more front leg bracket assemblies each comprises: a front leg having a front leg portion connected to a front leg base portion at a third angle; and a front leg bracket guide body defining a closed end bore adapted to receive a front edge of the at least one cornhole boards comprising a guide body defining a guide body closed end bore and connected to front leg bracket leg guide defining a through bore and a screw bore perpendicular to and connected to the through bore to receive a screw; wherein the front leg portion of the front leg is received within the through bore, such that the front leg bracket guide is vertically adjustable about the front leg.

10 The kit can also include a collapsible reducing wedge for insertion within the right leg guide body and/or the left leg guide body, a reducing shim for insertion within the one or more front leg bracket assemblies and a horizontal and angle slope level. It is noted that the reducing shims are used for legs that are less than 1.5 inches (38.1 mm) in width.

15 According to another embodiment of the present invention, 20 a kit for leveling one or more cornhole boards is disclosed. The kit comprises: at least one pair of back leg bracket assemblies, one or more front leg bracket assemblies, an alignment cable and alignment clips.

25 The back leg bracket assemblies comprising: a right leg bracket assembly and a left leg bracket assembly. The right leg bracket assembly has a right leg having a right leg portion connected to a right leg base portion at a first angle; a right back leg bracket guide having a right leg guide body defining a closed end bore adapted to receive a right leg of a back of one or more cornhole boards and connected to a right leg guide defining a right leg through bore and a right leg screw bore perpendicular to and connected to the right leg through bore adapted to receive a screw; wherein the right leg portion of the right leg is received within the right leg through bore, such that the right leg guide is vertically adjustable about the right leg portion. The left leg bracket assembly has a left leg having a left leg portion connected to a left leg base portion at a second angle; a left back leg bracket guide having a left leg guide body defining a closed end bore adapted to receive a left leg of a back of one or more cornhole boards and connected to a left leg guide defining a left leg through bore and a left leg screw bore perpendicular to and connected to the left leg through bore adapted to receive a screw; wherein the left leg portion of the left leg is received within the left leg through bore, such that the left leg guide is vertically adjustable about the left leg portion.

30 The one or more front leg bracket assemblies each comprises: a front leg having a front leg portion connected to a front leg base portion at a third angle; and a front leg bracket guide body defining a closed end bore adapted to receive a front edge of the at least one cornhole boards comprising a guide body defining a guide body closed end bore and connected to front leg bracket leg guide defining a through bore and a screw bore perpendicular to and connected to the through bore to receive a screw; wherein the front leg portion of the front leg is received within the through bore, such that the front leg bracket guide is vertically adjustable about the front leg.

35 40 45 50 55 60 65 60 The alignment cable has a first end and a second end separated by a length, the first end and the second end each having a retainer.

The left side alignment clip is adapted to mount to a left side of the first cornhole board. The left side alignment clip comprises: a left side alignment clip body with an a left side alignment clip first portion having a first end, a second end opposite the first end, a first side and a second side opposite the first side, a left side alignment clip second portion connected to the left side alignment clip first portion at the first end on the first side; and a left side alignment clip third portion connected to the left side alignment clip first portion at the second end on the second side defining at least one left side alignment piece.

The right side alignment clip adapted to mount to a right side of the second cornhole board. The right side alignment clip comprises: a right side alignment clip body with an a right side alignment clip first portion having a first end, a second end opposite the first end, a first side and a second side opposite the first side, a right side alignment clip second portion connected to the right side alignment clip first portion at the first end on the first side; and a right side alignment clip third portion connected to the right side alignment clip first portion at the second end on the second side defining at least one right side alignment piece.

The kit can also include a collapsible reducing wedge for insertion within the right leg guide body and/or the left leg guide body, a reducing shim for insertion within the one or more front leg bracket assemblies and a horizontal and angle slope level. It is noted that the reducing shims are used for legs that are less than 1.5 inches (38.1 mm) in width.

A method of leveling of aligning and leveling a first cornhole board and a second cornhole board for playing on uneven ground is also disclosed.

BRIEF DESCRIPTION OF THE DRAWINGS

FIG. 1 shows an example of a cornhole board.

FIG. 2 shows a cornhole board with a bracket leveling system.

FIG. 3 shows a first end view of the cornhole board with the bracket leveling system.

FIG. 4 shows a second end view of the cornhole board with the bracket leveling system.

FIG. 5a shows an exploded view of bracket assembly on a first end cornhole board with the bracket leveling system.

FIG. 5b shows a bracket assembly on a first end of the cornhole board.

FIG. 6a shows a side view of the right leg of the bracket assembly.

FIG. 6b shows a front view of the right leg of the bracket assembly.

FIG. 6c shows a top view of the right leg of the bracket assembly.

FIG. 6d shows a perspective view of the right leg of the bracket assembly.

FIG. 7a shows a front view of the right leg bracket.

FIG. 7b shows a top view of the right leg bracket.

FIG. 8a shows a side view of the right leg bracket.

FIG. 8b shows a cut away of the right leg guide.

FIG. 8c shows a cut away of the right bracket.

FIG. 9a shows a side view of the left leg bracket assem-

bly.

FIG. 9b shows a front view of the left leg bracket assembly.

FIG. 9c shows a top view of the left leg bracket assembly.

FIG. 9d shows a perspective view of the left leg bracket assembly.

FIG. 10a shows a front view of the left leg bracket.

FIG. 10b shows a top view of the left leg bracket.

FIG. 11a shows a side view of the left leg bracket.

FIG. 11b shows a cut away of the left leg guide.

FIG. 11c shows a cut away of the left leg bracket.

FIG. 12 shows a bracket assembly on the second end of the board.

FIG. 13 shows a cut away of the insert bracket assembly on the second end of the board.

FIG. 14a shows a side view of the front leg bracket.

FIG. 14b shows a front view of the front leg bracket.

FIG. 14c shows a top view of the front leg bracket.

FIG. 14d shows a perspective view of the front leg bracket.

FIG. 15a shows a side view of the left leg of the front bracket assembly.

FIG. 15b shows a front view of the left leg of the front bracket assembly.

FIG. 15c shows a top view of the left leg of the front bracket assembly.

FIG. 15d shows a perspective view of the left leg of the front bracket assembly.

FIG. 16a shows a top view of the rear leg bracket with the shim installed with 50% compression to little compression.

FIG. 16b shows a top view of the rear leg bracket with the shim installed with greater than 50% compression.

FIG. 17a shows a front view of the left rear leg shim at angle beta.

FIG. 17b shows a side view of the left rear leg shim at angle beta.

FIG. 17c shows a top view of the left rear leg shim at angle beta.

FIG. 17d shows a perspective view of the left rear leg shim at angle beta.

FIG. 17e shows a front view of the right rear leg shim at angle alpha.

FIG. 17f shows a side view of the right rear leg shim at angle alpha.

FIG. 17g shows a top view of the right rear leg shim at angle alpha.

FIG. 17h shows a perspective view of the right rear leg shim at angle alpha.

FIG. 18 shows the front leg bracket assembly with a leg of the cornhole board and reducing shim.

FIG. 19 shows a perspective view of the front leg bracket for holding compressible material to form a reducing shim.

FIG. 20a shows a front view of the level.

FIG. 20b shows a side view of the level.

FIG. 20c shows a top view of the level.

FIG. 20d shows a perspective view of the level.

FIG. 21a shows a left side alignment clip.

FIG. 21b shows a right side alignment clip.

FIG. 22a shows a left side alignment clip on the cornhole board.

FIG. 22b shows a right side alignment clip on the cornhole board.

FIG. 23a shows an alignment cable with solid ends.

FIG. 23b shows an alignment cable with looped ends.

FIG. 24a shows a side view of the right surface alignment line attachment clip.

FIG. 24b shows a top view of the right surface alignment line attachment clip.

FIG. 24c shows a perspective view of the right surface alignment line attachment clip.

FIG. 25a shows a side view of the left surface alignment line attachment clip.

FIG. 25b shows a top view of the left surface alignment line attachment clip.

FIG. 25c shows a perspective view of the left surface alignment line attachment clip.

FIG. 26a-26b shows a method of leveling the cornhole board.

FIG. 27 shows a method of leveling the cornhole boards laterally.

FIG. 28 shows a method of adjusting the slop of the cornhole boards.

FIG. 29 shows a top view of placing the first board on the ground across from a second board, connecting alignment clips of the first and second boards using an alignment cable with the first board and second board not in alignment with a length of the alignment cable.

FIG. 30a shows a top view of the first and second boards moved to be in alignment with a length of the alignment cable.

FIG. 30b shows a side view of FIG. 30a.

DETAILED DESCRIPTION

FIGS. 2-4 show a corn hole board 10 with front leg bracket assemblies 40, 41 on the first end or front end 2a and back leg bracket assemblies 20, 21 on the second end or back end 2b to level the corn hole board 10 relative to the ground 6. Both the back leg bracket assemblies 20, 21 and the front leg bracket assemblies 40, 41 are individually adjustable to raise or lower the front end 2a or back end 2b of the corn hole board 10.

FIGS. 5a-11c show the back leg bracket assemblies 20, 21. The right back leg bracket assembly 20 has a right leg 22 of a leg portion 24 and a base portion 23 as shown in FIGS. 6a-6d and a right back leg bracket guide 29 shown in FIGS. 7a-8c. The left back leg bracket assembly 21 has a left leg 29 of a leg portion 25 and a base portion 26 as shown in FIGS. 9a-9d and a left back leg bracket guide 30 shown in FIGS. 10a-11c.

The base portion 23 of the right leg 22 has a first surface 23a and a second surface 23b, opposite the first surface 23a. The second surface 23b contacts the ground 6. The leg portion 24 has a first end 24a and a second end 24b. The second end 24b of the leg portion 23 is attached to the first surface 23a of the base portion 23 at an angle alpha. The angle alpha is preferably between 20-30 degrees. More preferably, the angle alpha is 27 degrees.

Referring to FIGS. 7a-8c, the right back leg bracket guide 29 has a guide body 27 defining a closed end bore 27a and is connected to a leg guide 28. The leg guide 28 defines a through bore 28a and a screw bore 28b perpendicular to and connected to the through bore 28a.

The leg guide 28 is fixed to the guide body 27 at the same angle alpha as the right leg 22 to the base portion 23. The screw bore 28b receives a screw 33 that abuts the right leg 22 received within the through bore 28a.

The base portion 26 of the left leg 29 has a first surface 26a and a second surface 26b, opposite the first surface 26a. The second surface 26b contacts the ground 6. The leg portion 25 has a first end 25a and a second end 25b. The second end 25b of the leg portion 25 is attached to the first surface 26a of the base portion 26 at an angle beta. The angle beta is preferably between 20-30 degrees. More preferably, the angle beta is 27 degrees. In one embodiment, the angle alpha equals the angle beta.

Referring to FIGS. 9a-11c, the left back leg bracket guide 30 has a guide body 31 defining a closed end bore 31a and is connected to a leg guide 32. The leg guide 32 defines a through bore 32a and a screw bore 32b perpendicular to and connected to the through bore 31a. The leg guide 31 is fixed

to the guide body 32 at the same angle beta as the left leg 29 to the base portion 26. The screw bore 32b receives a screw 33 that abuts the left leg 29 received within the through bore 31a.

As shown in FIG. 5a, the legs 4, 5 of the cornhole board 10 are inserted into bore 27a, 31a of the guide bodies 27, 31. The leg portion 24, 25 is inserted into the through bore 28a, 32a. A screw 35 is received within the screw bore 28b, 32b. The height of the leg 4, 5 is adjusted by moving the guide body 27, 31 along the length of the leg portion 24, 25 and fixed in place with the screw 35 which interacts with the leg 24, 25.

FIG. 5b shows an initial position in which the leg 4, 5, of the cornhole board 10 is at the least amount of height added to raise the back end 2b of the cornhole board 10.

FIGS. 12-13 shows the front bracket assemblies 40, 41 which can be mounted to the first or front end 2a of the cornhole board 10. The front bracket assemblies 40, 41 engage at least a front edge 2f of the cornhole board 10.

Referring to FIGS. 14a-14d, the front bracket assemblies 40, 41 each have a guide body 55 defining a closed ended bore 55a which receives the front edge 2f. It is noted that the front edge 2f can be a board with 2 inches (50.8 mm) or less of width. Attached to the guide body 55 is a leg guide 56. The leg guide 56 has a through hole 56a parallel to the closed end bore 55a of the guide body 55.

FIGS. 15a-15d show the front legs 54 of which a portion are received by the through hole 56a of the leg guide 56. The front legs 54 have a base portion 53 connected to a leg portion 52. The leg portion 52 has a first end 52a and a second end 52b. The base portion 53 has a first surface 53a and a second surface 53b, opposite the first surface 53a. The second surface 53b contacts the ground 6. The second end 52b of the leg portion 52 is attached to perpendicular to the first surface 53a of the base portion 53.

The height of the front end 2a of the cornhole board 10 can be raised and adjusted to different heights based on movement of the leg portion 52 within the through hole 56a of the leg guide 56.

FIGS. 17a-17d show a collapsible reducing wedge 60 that can be inserted between the left back leg 4 and the left back leg bracket guide 30 depending on the thickness of the left back leg 4. It is noted that the collapsible reducing wedge 60 is angled at an angle beta to match the leg guide 32 of the left leg bracket guide 30.

FIGS. 17e-17h shows a collapsible reducing wedge 63 that can be inserted between the right back leg 5 and the right back leg bracket guide 29 depending on the thickness of the right back leg 5. It is noted that the collapsible reducing wedge 63 is angled at an angle alpha to match the leg guide 28 of the right leg bracket guide 29.

If the thickness of the right and left back legs 4, 5 is not enough to fill the closed end bore 27a, 31a, the collapsible reducing wedge 60, 63 can be used as a shim to fill the closed end bore 27a, 31a. The collapsible reducing wedge 60, 63 each have a collapsible material 62 attached to a rigid shim plate 61. In a non-compressed state, the collapsible material has 62 a distance d3.

FIG. 16a shows the board leg 4, 5 of a first thickness w1. The collapsible reducing wedge 60 is inserted within the closed end bore 27a, 31a adjacent to the board leg 4, 5, with the collapsible material reduced to a distance d1. In this figure the board leg 4, 5 has a thickness of approximately $\frac{3}{4}$ inch. FIG. 16b shows a board leg 4, 5 with a second thickness w2, greater than thickness w1, but still not a thickness large enough to fill the closed end bore 27a, 31a. The thickness of the board legs 4, 5 is greater than $\frac{3}{4}$ inch.

As shown, the collapsible material is collapsed to a distance d_2 , less than d_1 . Therefore, the collapsible reducing wedge **60** is adaptable to act as a shim for various thicknesses of the legs **4, 5**.

FIGS. 18-19 show a reducing shim **65** for filling the space within the closed end bore **55a** of the guide body of the front bracket assemblies **40, 41** after the front edge **2f** of the cornhole board has been inserted into the closed end bore **55a**. The reducing shim **65** has a C-shaped rigid body **65** defining an opening **66** for receiving a collapsible material **67**.

FIGS. 26a-28 are a method of aligning and leveling cornhole boards for playing on uneven ground.

In a first step (step 302), a first cornhole board **10a** is placed on the ground opposite a second cornhole board **10b**. It is noted that the first end **2a** of each of the first cornhole board **10a** and the second cornhole board **10b** face each other as shown in FIG. 29.

An alignment clip **70, 71**, is then placed on the back corner edges **2g** of the first and second cornhole boards **10a, 10b**. FIGS. 25a-25c shows a left side alignment clip **70** and FIGS. 24a-24c shows a right side alignment clip **71** (step 304).

FIG. 22a shows the left side alignment clip **70** on back corner edge **2g** near leg **4** of the first cornhole board **10a**. FIG. 22b shows the right side alignment clip **71** on back edge **2g** near leg **5** of the second cornhole board **10b**. It is noted that the right side alignment clip **71** could be used near leg **4** of the first cornhole board **10a** and the left side alignment clip **70** used near leg **5** of the second cornhole board **10b**. It is noted that the right side alignment clip **71** is a mirror image of the left side alignment clip **70**.

Referring back to FIGS. 24a-25c, the alignment clips **70, 71** each have a body **72** with a first portion **73** with a first end **73a** and a second end **73b** and a first side **73c** and a second side **73d**. Connected to the first portion **73** at the first end **73a** on the first side **73c** is a second portion **74**. Connected to the first portion **73** at the second end **73b** on the second side **73d** is a third portion **75** which defines at least one hook **76**.

The alignment clips **70, 71** are placed onto the cornhole boards **10a, 10b** such that the corner edge **2g** contacts the first portion **73**, the second portion **74** is received underneath and behind the second end **2b** between the leg **4, 5** and the corner edge **2g**, and the third portion **75** is adjacent to second end **2b**.

Referring back to FIGS. 26a-26b, the alignment clips **70, 71** attached to the first and second cornhole boards **10a, 10b** are connected together using an alignment cable **80, 81** (step 306) as shown in FIG. 29.

FIG. 23b shows an alignment cable **81** with a first end **81a** separated from a second end **81b** by a length **81c**. The length **81c** of the alignment cable can be 35 feet or 41 feet long. Markers **82** may be present along the length **81c** of the alignment cable **81** to indicate 27 feet between each first end **2a** of the first and second cornhole boards **10a, 10b**. While not shown, the markers **82** can also indicate 33 feet between the first end **2a** of the first cornhole board **10a** and the first end **2a** of the second cornhole board **2a**. At the first end **81a** and the second **81b** are loops **84** that can be accepted around the hooks **76** of the alignment clips **70, 71**.

Alternatively, alignment clips **78, 79** are placed onto the cornhole boards **10a, 10b** in step 304. The alignment clips **78, 79** have each have a body **72** with a first portion **73** with a first end **73a** and a second end **73b** and a first side **73c** and a second side **73d**. Connected to the first portion **73** at the first end **73a** on the first side **73c** is a second portion **74**. Connected to the first portion **73** at the second end **73b** on

the second side **73d** is a third portion **87** which defines at least two flanges **85a-85c** which define holes **86a, 86b**. The alignment clips **78, 79** are placed on the cornhole boards **10a, 10b**, such that the corner edge **2g** contacts the first portion **73**, the second portion **74** is received underneath and behind the second end **2b** between the leg **4, 5** and the corner edge **2g**, and the third portion **75** is adjacent to second end **2b**.

FIG. 23a shows an alignment cable **80** with a first end **80a** 10 separated from a second end **80b** by a length **80c**. The length **80c** of the alignment cable can be 35 feet or 41 feet long. Markers **82** may be present along the length **80c** of the alignment cable **80** to indicate 27 feet between each first end **2a** of the first and second cornhole boards **10a, 10b**. While 15 not shown, the markers can also indicate 33 feet between the first end **2a** of the first cornhole board **10a** and the first end **2a** of the second cornhole board **2a**. At the first end **80a** and the second **80b** are solid pieces **83** that can be accepted into the openings **86a-86b** between the flanges **85a-85c** of the 20 alignment clips **78, 79** in step 306 to connect opposing cornhole boards **10a, 10b** together.

The first and/or second cornhole boards **10a, 10b** are moved to pull the alignment cable taut (step 308).

Next, it is determined whether the top or bottom edges **2i, 2j** of the sides **2h** of the first and second cornhole boards **10a, 10b** are aligned with the length **80c, 81c** of the alignment cable **80, 81** (step 310). If the top or bottom edges **2i, 2j** of the sides **2h** of the first and second cornhole boards **10a, 10b** are aligned with the length **80c, 81c** of the alignment cable **80, 81** as shown in FIGS. 30a-30b, the method continues to step 314. If the top or bottom edges **2i, 2j** of the sides **2h** of the first and second cornhole boards **10a, 10b** are not aligned with the length **80c, 81c** of the alignment cable **80, 81** as shown in FIG. 29, the cornhole boards **10a, 10b** are moved laterally towards or away from the alignment cable **80, 81** 35 (step 312) as shown in FIGS. 30a-30b and the method continues to step 314.

The cornhole boards **10a, 10b** are then leveled (step 314). Referring to FIG. 27, the leveling of the cornhole boards **10a, 10b** includes the sub-steps of placing a horizontal and angle slope level **100** at first end **2a** of each of the cornhole boards **10a, 10b** (step 350) and if the cornhole board **10a, 10b** is not level (step 352), placing one or more front leg bracket assemblies **40, 41** on the front edge **2f** and raising or 45 lowering the guide bodies **55** on the front legs **54** until the cornhole board **10a, 10b** is level (step 354). The screw **35** is tightened to engage the leg portion **52** to maintain the one or more front leg bracket assemblies **40, 41**. The method continues to step 316.

The horizontal and angle slope level **100** is shown in FIGS. 20a-20d. The horizontal and angle slope level **100** has a body **101** which is L-shaped and has a first portion **102** connected to a second portion **103** at a right angle. The first portion **102** has an outer surface **102a** and an inner surface **102b**. The inner surface **103b** contacts the cornhole board **10a, 10b**. Mounted to the outer surface **102a** of the first portion **102** is a sloped body **104** defining a bore **105** for receiving a first level **110**. The sloped body **104** is higher at a first end **104a** than the second end **104b**. The first level **110** 55 determines the angle slope of the cornhole boards **10a, 10b** when placed on the front edge **2f**. The second portion **103** has an outer surface **103a** and an inner surface **103b**. Mounted to an outer surface **103b** of the second portion **103** is a body **107** defining a bore **108** for receiving a second level **111**. The second level **111** determines the horizontal slope of the cornhole boards **10a, 10b**. It is noted that the which slope 60 being measured—horizontal or angle, is determined by

which level is placed adjacent to the top surface $2c$ of the cornhole board $10a, 10b$. The level measuring angle slope is set to be "level" at 10 degrees.

Step 316 of adjusting the slope has sub-steps shown in FIG. 28 of placing the horizontal and angle slope level 100 at top edge $2i$ of the side $2h$ of each of the cornhole boards $10a, 10b$ (step 350) and if the cornhole board $10a, 10b$ is not level (step 356), placing the back leg bracket assemblies 20, 21 on the legs 4, 5 of the cornhole boards $10a, 10b$ and raising or lowering the left back bracket guide 30 on left leg 29 and the right back leg bracket guide 29 on right leg 22 until the cornhole board $10a, 10b$ is level (step 360). Screws 35 are tightened to engage the right leg 22 and the left leg 29 to maintain the back bracket assemblies 20, 21. The method continues to step 318.

The alignment cable, alignment clips and level are removed (step 318) and the method ends.

It is noted that a kit for leveling one or more cornhole boards would include front leg bracket assemblies 40, 41, back leg bracket assemblies 20, 21 and the horizontal and angle slope level 100.

It is noted that a kit for aligning and leveling cornhole boards for playing on uneven ground would include front leg bracket assemblies 40, 41, back leg bracket assemblies 20, 21, the horizontal and angle slope level 100, alignment cables 80, 81 and alignment clips 78, 79, 70, 71.

Accordingly, it is to be understood that the embodiments of the invention herein described are merely illustrative of the application of the principles of the invention. Reference herein to details of the illustrated embodiments is not intended to limit the scope of the claims, which themselves recite those features regarded as essential to the invention.

What is claimed is:

1. A kit for leveling one or more cornhole boards comprising:

at least one pair of back leg bracket assemblies comprising:

a right leg bracket assembly comprising: a right leg having a right leg portion connected to a right leg base portion at a first angle; a right back leg bracket guide having a right leg guide body defining a closed end bore adapted to receive a right leg of a back of one or more cornhole boards and connected to a right leg guide defining a right leg through bore and a right leg screw bore perpendicular to and connected to the right leg through bore adapted to receive a screw; wherein the right leg portion of the right leg is received within the right leg through bore, such that the right leg guide is vertically adjustable about the right leg portion;

a left leg bracket assembly comprising: a left leg having a left leg portion connected to a left leg base portion at a second angle; a left back leg bracket guide having a left leg guide body defining a closed end bore adapted to receive a left leg of a back of one or more cornhole boards and connected to a left leg guide defining a left leg through bore and a left leg screw bore perpendicular to and connected to the left leg through bore adapted to receive a screw; wherein the left leg portion of the left leg is received within the left leg through bore, such that the left leg guide is vertically adjustable about the left leg portion; and one or more front leg bracket assemblies each comprising: a front leg having a front leg portion connected to a front leg base portion at a third angle; a front leg bracket guide body defining a closed end bore adapted to receive a front edge of the at least

one cornhole boards comprising a guide body defining a guide body closed end bore and connected to a front leg bracket leg guide defining a through bore and a screw bore perpendicular to and connected to the through bore to receive a screw; wherein the front leg portion of the front leg is received within the through bore, such that the front leg bracket leg guide is vertically adjustable about the front leg.

2. The kit of claim 1, wherein the first angle and the second angle are 27 degrees.

3. The kit of claim 1, wherein the first angle and the second angle are between 20 to 30 degrees.

4. The kit of claim 1, wherein the left leg further comprises: a left leg base portion attached to the left leg on a left leg base portion first surface and adapted to engage a ground surface on a left leg base portion second surface and the right leg further comprises a right leg base portion attached to the right leg on a right leg base portion first surface and adapted to engage a ground surface on a right leg base portion second surface.

5. The kit of claim 1, further comprising a collapsible reducing wedge comprising a rigid shim plate attached to a collapsible material for insertion within the closed end bore of the right leg guide body and/or the closed end bore of the left leg guide body.

6. The kit of claim 1, further comprising a reducing shim comprising a C-shaped rigid body defining an opening for receiving a collapsible material, the reducing shim being received in the closed end bore of the front leg bracket guide body of the one or more front leg bracket assemblies.

7. The kit of claim 1, further comprising a horizontal and angle slope level comprising: an L-shaped body having a first portion with a sloped body defining a first level bore receiving a first level measuring a slope angle of the one or more cornhole boards and a second portion with a body defining a second level bore receiving a second level measuring a horizontal level between side edges of the one or more cornhole boards.

8. A kit for leveling a first cornhole board and a second cornhole board and setting a regulation distance between the first cornhole board and the second cornhole board, the kit comprising:

a pair of back leg bracket assemblies for each of the first cornhole board and the second cornhole board comprising:

a right leg bracket assembly comprising: a right leg having a right leg portion connected to a right leg base portion at a first angle; a right back leg bracket guide having a right leg guide body defining a closed end bore adapted to receive a right leg of a back of one or more cornhole boards and connected to a right leg guide defining a right leg through bore and a right leg screw bore perpendicular to and connected to the right leg through bore adapted to receive a screw; wherein the right leg portion right leg is received within the right leg through bore, such that the right leg guide is vertically adjustable about the right leg portion;

a left leg bracket assembly comprising: a left leg having a left leg portion connected to a left leg base portion at a second angle; a left back leg bracket guide having a left leg guide body defining a closed end bore adapted to receive a left leg of a back of one or more cornhole boards and connected to a left leg guide defining a left leg through bore and a left leg screw bore perpendicular to and connected to the left leg through bore adapted to receive a screw; wherein

11

the left leg portion of the left leg is received within the left leg through bore, such that the left leg guide is vertically adjustable about the left leg portion; one or more front leg bracket assemblies for each of the first cornhole board and the second cornhole board, each front leg bracket assembly comprising: a front leg having a front leg portion connected to a front leg base portion at a third angle; a front leg bracket guide body defining a closed end bore adapted to receive a front edge of the at least one cornhole boards comprising a guide body defining a guide body closed end bore and connected to a front leg bracket leg guide defining a through bore and a screw bore perpendicular to and connected to the through bore to receive a screw; wherein the front leg portion of the front leg is received within the through bore, such that the front leg bracket leg guide is vertically adjustable about the front leg; and an alignment cable having a first end and a second end separated by a length, the first end and the second end each having a retainer; a left side alignment clip adapted to mount to a left side of the first cornhole board, the left side alignment clip comprising: a left side alignment clip body with an a left side alignment clip first portion having a first end, a second end opposite the first end, a first side and a second side opposite the first side, a left side alignment clip second portion connected to the left side alignment clip first portion at the first end on the first side; and a left side alignment clip third portion connected to the left side alignment clip first portion at the second end on the second side defining at least one left side alignment piece; and a right side alignment clip adapted to mount to a right side of the second cornhole board, the right side alignment clip comprising: a right side alignment clip body with an a right side alignment clip first portion having a first end, a second end opposite the first end, a first side and a second side opposite the first side, a right side alignment clip second portion connected to the right side alignment clip first portion at the first end on the first side; and a right side alignment clip third portion connected to the right side alignment clip first portion at the second end on the second side defining at least one right side alignment piece.

9. The kit of claim 8, wherein the right side alignment piece is at least one right side hook and the left side alignment piece is at least one left side hook.

10. The kit of claim 9, wherein the retainer is a loop received by the at least one right side hook and the at least one left side hook.

11. The kit of claim 8, wherein the alignment cable further comprises markers along the length indicated 27 feet between the first cornhole board and the second cornhole board.

12. The kit of claim 8, wherein the right side alignment piece is at least two right side flanges defining a plurality of holes and the left side alignment piece is at least two left side flanges defining a plurality of holes.

13. The kit of claim 12, wherein the retainer is a solid piece received within one of the plurality of openings defined by the at least two right side flanges and the at least two left side flanges.

14. The kit of claim 8, further comprising a horizontal and angle slope level comprising: an L-shaped body having a first portion with a sloped body defining a first level bore receiving a first level measuring a slope angle of the one or

12

more cornhole boards and a second portion with a body defining a second level bore receiving a second level measuring a horizontal level between side edges of the one or more cornhole boards.

5 15. The kit of claim 8, further comprising a collapsible reducing wedge comprising a rigid shim plate attached to a collapsible material for insertion within the closed end bore of the right leg guide body and/or the closed end bore of the left leg guide body.

10 16. The kit of claim 8, further comprising a reducing shim comprising a C-shaped rigid body defining an opening for receiving a collapsible material, the reducing shim being received in the closed end bore of the front leg bracket guide body of the one or more front leg bracket assemblies.

15 17. The kit of claim 8, further comprising a horizontal and angle slope level comprising: an L-shaped body having a first portion with a sloped body defining a first level bore receiving a first level measuring a slope angle of the one or more cornhole boards and a second portion with a body defining a second level bore receiving a second level measuring a horizontal level between side edges of the one or more cornhole boards.

20 18. A method of aligning and leveling a first cornhole board and a second cornhole board for playing on uneven ground comprising:

25 placing the first cornhole board on the uneven ground opposite a second cornhole board on the uneven ground, such that a first end of the first cornhole board is facing a first end of the second cornhole board; placing a first alignment clip on a left side back corner edge of the first cornhole board and a second alignment clip on a right side back corner edge of the second cornhole board;

30 connect the first alignment clip of the first cornhole board to the second alignment clip of the second cornhole board with an alignment cable;

35 moving the first cornhole board or the second cornhole board to pull the alignment cable taut while connected to the first alignment clip and the second alignment clip;

40 aligning first cornhole board edges and second cornhole board edges with a length of the alignment cable through lateral movement of the first cornhole board and the second cornhole board;

45 leveling the first cornhole board and the second cornhole board with a level;

50 adjusting a slope of the first cornhole board and the second cornhole board; and

removing the alignment cable, alignment clips and the level from the first cornhole board and second cornhole board.

55 19. The method of claim 18, wherein leveling the first cornhole board and the second cornhole board with the level comprises: placing a horizontal and angle slope level at the first end of each of the first and second cornhole boards and when either of the first cornhole board or the second cornhole board is not level, placing one or more front leg bracket assemblies on a front edge of the first cornhole board and/or the second cornhole board and raising or lowering guide bodies on one or more front legs of the front leg bracket assemblies until the first cornhole board and/or the second cornhole board is level; and tightening a screw received within the guide bodies to engage a leg portion of the one or more front legs to maintain the one or more front leg bracket assemblies in place.

20. The method of claim 18, wherein adjusting the slope of the first cornhole board and the second cornhole board comprises:

placing a horizontal and angle slope level at a top edge of a side of each of the first cornhole board and the second cornhole board, and when either of the first cornhole board and/or the second cornhole board is not level, placing a right back leg bracket assembly on a right back leg of the first and/or second cornhole boards, placing a left back leg bracket assembly on a left back leg and raising or lowering a left back bracket guide of the left back leg bracket assembly on the left leg and a right back leg bracket guide of the right back leg bracket assembly on the right leg until the first and/or second cornhole boards are level; tightening a screw received within the right back leg bracket guide to engage a right leg portion of the right leg to maintain the right back leg bracket assembly in place; and tightening a screw received within the left back leg bracket guide to engage a left leg portion of the left leg to maintain the left back leg bracket assembly in place.
